UNITED STATES PATENT OFFICE.

SARAH SORKIN, OF NEW YORK, N. Y.

BRASSIÈRE.

1,190,602.

Specification of Letters Patent. Patented July 11, 1916.

Application filed November 26, 1915. Serial No. 63,517.

To all whom it may concern:

Be it known that I, SARAH SORKIN, a subject of the Czar of Russia, residing at New York, in the county of New York and 5 State of New York, have invented certain new and useful Improvements in Brassières; and I declare the following to be a full, clear, and exact description of the invention, such as will enable others skilled in the 10 art to which it appertains to make and use the same.

This invention relates to improvements in corset covers or brassières.

One object of the invention is to so construct a brassière that it will perform the double function of a corset cover and brace for holding the shoulders of the wearer drawn back in proper position to prevent stooping.

20 Another object is to so construct a device of this character that it will force the shoulder blades or scapulae inward.

Another object of the invention is to provide a tight fitting body garment having an 25 elastic strip arranged across the back thereof with inelastic strips connected adjacent the ends of said elastic strip and adapted to extend under the bust of the wearer to assist in affording resistance to the elastic strip 30 when stretched.

With these and other objects in view, the invention consists of certain novel features of construction, and the combination and arrangement of parts to be hereinafter fully 35 described and claimed.

In the accompanying drawings, Figure 1 represents a perspective view of this improved brassière taken from the front; Fig. 2 is a rear elevation thereof; Fig. 3 is a longitudinal section taken on line 3—3 of Fig. 2 with the straps in retracted position; Fig. 4 is a similar view with the straps shown stretched; Fig. 5 is a vertical transverse section through the strap carrying back portion.

45 In the embodiment illustrated a tight fitting corset cover or brassière 1 is shown which may be of any ordinary or desired construction, being here shown provided with longitudinally extending reinforcing rows of stitching 2 around the body portion thereof, but obviously these may be omitted if desired and the brassière made plain throughout the body.

55 The back B of the brassière embodying this invention has one or more elastic straps

3 extending transversely thereacross from one armhole to the other, three of said straps being here shown spaced vertically on the back B and secured at their opposite ends 60 adjacent to or at the reinforced armhole portion of the garment, the straps increasing in length from the upper toward the lower to adapt them to conform to the width of the back B as it increases from the top toward 65 the center, as is shown clearly in Figs. 1 and 2. These elastic strips or straps 3 are preferably composed of elastic webbing such as is usually employed for garters and the like, and they are of a length when stretched 70 to their full extent equal to the width of the back of the garment to which they are to be applied, so that when in normal unstretched position, before being placed on the wearer, they will be of less length than the width 75 of the back of the garment, thereby causing a fullness at the center of said back between the unattached portions of the straps. These straps 3 are not only secured at their 80 ends to the garment but are stitched longitudinally along the edges thereof from each end toward the center to form casings 4 for the reception of reinforcing or stiffening members 5 here shown in the form of covered steel strips similar to those employed 85 in boning corsets. These stiffening members 5, two of which are employed in connection with each strap 3, are arranged in the casings 4 and their inner ends are arranged in close proximity when the cover 90 is removed from the wearer and the straps are in unstretched position, the combined length of the two reinforcing strips being 95 substantially equal to the length of the strap in connection with which they are used before said strap is stretched, so that when the strap is placed under tension the ends of these reinforcing strips will be separated at the center of the back of the garment. 100 By so forming these elastic strips and connecting them with the garment and by placing the stiffening strips 5 in the casings formed thereby, when the garment is donned by the wearer the straps will be stretched to their full extent, and in addition to forcing 105 the shoulders of the wearer back the reinforcing strips will bear on the shoulder blades or scapulae and force them inwardly, thereby assisting in causing the wearer to hold her shoulders in proper position.

110 Two inelastic straps or strips 6 and 7 are here shown used in connection with the

elastic strips 3 and are secured at one end to the armholes of the garment at the rear thereof adjacent the connection of the strips 3 and are designed to pass forward under 5 the bust of the wearer and have their free ends connected by a buckle 8 or any suitable fastening means. These inelastic strips 6 and 7 have their connected ends shown inclined downwardly and inwardly to adapt 10 them to conform to the shape of the armholes to which they are applied, and these strips coöperate with the elastic strips 3 affording a resistance thereto and prevent undue pulling or binding of the front portion 15 of the garment across the bust, such as would be likely to occur if these strips 6 and 7 were not employed and also to prevent the front portions of the armholes from cutting into the arms of the user.

20 From the above description it will be obvious that when the garment is not in use the strips 3 will be contracted and the unstitched portions of the garment back B between the inner ends of the rows of stitching 25 which connect the straps to the garment and also form the casings 4, will form a fullness between said ends of the rows of stitching to provide for the stretching of the strips 3 when the garment is applied, and 30 this fullness, when said strips are so stretched to their full extent, will be straightened out to conform to the back of the wearer and present a smooth unpuckered appearance when in use. From the 35 above description it will thus be understood that this brassière in addition to performing its ordinary function of a corset cover, operates also as a brace for the wearer, forcing her to throw back her shoulders in proper position and thus prevent stooping.

40 The inelastic strain resisting strips 6 and 7 render the garment comfortable by preventing the front portions of the armholes from cutting into the arms of the wearer 45 and may be adjusted to afford greater or less resistance, according to the wishes of the user.

50 By using the inelastic strips 6 and 7 and passing them under the bust of the wearer, it will not be necessary that the front portion 55 of the corset cover be made tight fitting, as these strips will offer the necessary resistance to the stretching of the strips 3

without any strain being exerted on the front portion of the corset cover.

55

I claim:

1. A body garment having an elastic strip extending transversely across the back thereof and secured at its opposite ends adjacent the armholes of the garment, said strip being of a length less than the width of the garment back when it is in normal unstretched position, and corresponding in length to the width of said back when the strip is stretched, and inelastic strips secured at one end to the rear portion of the armholes of the garment adjacent the connection of the ends of said elastic strip, said inelastic strips being adapted to pass around under the arms of the wearer to the front thereof and be secured together at their free ends under the bust of the wearer.

2. A tight fitting body garment having a plurality of elastic strips extending transversely across the back thereof, said strips being spaced laterally from each other and secured at their opposite ends adjacent the opposite armholes of the garment and having rows of stitches extending longitudinally thereof in laterally spaced relation from 80 their ends toward their center, said rows connecting said strips with the back of the garment and terminating at their inner ends at points spaced from each other, the strips when in unstretched position being of less 85 length than the width of the garment back, thereby producing in the garment between the unstitched portions of each strip a fullness to provide for the stretching of the strips when the garment is applied without 90 danger of tearing the garment, inelastic strips each having one end inclined downwardly and inwardly and secured to the rear portion of the armholes of the garment adjacent the connected ends of the elastic strips, said inelastic strips being adapted to pass under the arms of the wearer, and means for securing their free ends together 95 below the bust of the wearer.

In testimony whereof I have hereunto set 100 my hand in presence of two subscribing witnesses.

SARAH SORKIN.
